UNITED STATES PATENT OFFICE

ALBERT MILTON BARRON, OF PHILADELPHIA, PENNSYLVANIA

STARTING BLOCK

Application filed October 8, 1929. Serial No. 398,195.

This invention relates to certain revisions and refinements in starting blocks for athletic track use, such as for instance, the type of starting blocks shown in Patent No. 1,709,832, granted to me under date of April 23, 1929.

Starting blocks of this character are devised with a view toward obviating a stumbling and uncertain start on a running track and to afford a splendid and dependable means to facilitate a vigorous spurt from the starting point and enable the runner to literally spring or bound forth into immediate and energetic motion.

In developing the structures of this application, I have evolved and produced two distinguishable sets of starting blocks such as differ in minor details to enable them to be successfully employed on an indoor track in a gymnasium or the like, or on an out-of-doors track in an athletic stadium.

My principal aim is to improve upon and simplify the structure shown and described in the aforesaid patent and to provide characteristically different front and rear starting blocks, and to embody in the rear starting block an adjustable foot rest such as will promote greater comfort by affording the proper degree of inclination, and thereby insure firm footing.

Generically stated, each set of blocks comprises front and rear foot rests having novel means for detachable association with the track whereby to permit the blocks to be arranged in a desirable longitudinally spaced relationship as well as in proper transverse spaced relationship.

Other features and advantages will become more readily apparent from the following description and drawings.

40 In the drawings:

Figure 1 is a top plan view of an out-of-doors track showing the particular species of blocks employed for such outside use.

Figure 2 is an edge or end elevational view 45 of the structure seen in Figure 1.

Figure 3 is a view like Figure 1 showing an indoor track with the indoor starting block.

Figure 4 is a longitudinal sectional view 50 showing the end or cross sectional shape of the blocks.

Figure 5 is an enlarged central transverse or vertical section on the lines 5—5 of Figure 6.

Figure 6 is a rear view of the outside rear starting block.

Figure 7 is a corresponding view of the front starting block.

Figure 8 is a rear view of the rear indoor starting block.

Figure 9 is a corresponding view of the front indoor block.

Figure 10 is an enlarged fragmentary section showing the attachment of one of the floor anchoring studs of the type of block shown in Figure 8.

Figure 11 is an enlarged fragmentary sectional and elevational view showing the anchoring stake attachment of the type of blocks seen in Figures 6 and 7, the sections being approximately on the plane of the line 11—11 of Figure 6.

Attention is first invited to the out-of-doors type or species of starting block seen in Figures 1, 2, 5, 6, and 7.

As seen in Figures 1 and 2, the reference character 12 designates an ordinary out-of-doors running track, such as is shown on the modern athletic stadium. The front block is distinguished by the reference character 13 and the rear block by the reference character 14. These differ slightly in construction. The front block is preferably of a sturdy piece of wood and of substantially triangular cross section as indicated at 15. This provides a substantially flat bottom for rest on the track and a slanting foot resting surface. This is preferably covered with a sheet of rubber 16, or analogous anti-slipping material.

Secured by bolts 17 (see Figure 11) to the under side and at opposite ends are the laterally directed end portions 18 of the downwardly inclined pointed ground anchoring stakes 19. These permit the block to be firmly anchored in the ground as shown in Figure 2.

The rear block 14 is located on the side of the track opposite to that of the front block. The rear block is of sectional construction. It includes a relatively stationary base 20

having anchoring stakes 19 of the construction already described. These are slightly larger than the front stakes but are of the same form and are attached to the base 20 in the manner shown in Figure 11. The relatively movable and adjustable block 21 constitutes a foot rest and this is of triangular cross sectional shape and provided on its front with an anti-slipping rubber pad or cover 22 having a flap or apron 23 extending down across the front bevelled edge of the base 20.

It will be noted that the reference characters 24 and 25 designate leaves which are hingedly connected together to hinge the foot rest 21 to the base 20. On the rear center of the part 21 is a toothed strip or rack member 26 which constitutes a keeper for cooperation with a pawl 27. This pawl is hingedly mounted on brackets 28 on the base and the pawl is actuated by springs 29 to engaging position. This allows the angularity or inclination of the foot resting surface of the rear block to be adjusted according to the desire of the runner.

With this arrangement the blocks 13 and 14 are simply driven down by way of the stakes into the ground and suitably anchored. Thus, it is possible to arrange the blocks in proper longitudinal and transverse spaced relationship to facilitate dependable footing.

In Figure 3, the reference character 30 designates an indoor track on which the front and rear blocks 31 and 32 are detachably mounted. The rear block 32 is somewhat in the nature of a threshold in that it includes a relatively thin block 33 having a slanting surface 34 for the ball or toe portion of the foot.

40 The front block includes a body portion 35 of a shape like that shown at 15 in Figure 2. Here I provide a corrugated anti-slipping rubber pad 36 for the top. The inclination of this padded top surface is gradual in comparison to the bevelled surface 34 of the rear block 32. Both of these blocks are provided on their under side and adjacent their opposite ends with attaching plates 37 carrying tapered studs 38 adapted to be fitted removably into sockets 39 bored, drilled, or otherwise formed in the floor, as seen in Figure 4. This enables the blocks to be bodily removed and adjusted.

A careful consideration of the description in connection with the drawings will enable the reader to obtain a clear understanding of the refinements and improvements embodied in this new arrangement of starting block construction; therefore, a more lengthy description is regarded as unnecessary.

60 Minor changes in shape, size and rearrangement of details coming within the field of invention claimed may be resorted to in actual practice if desired.

65 I claim:

As a new product of manufacture, a rear starting block comprising a base, a triangular section hingedly secured to said base, said section having a toothed rack, and a spring pressed latch pawl carried by said base and having its free end selectively cooperable with the teeth of said rack.

In testimony whereof I affix my signature.

ALBERT MILTON BARRON.
